H. F. YEAKEL

SANITARY WATER CLOSET SEAT

Filed Dec. 28, 1923

WITNESS

R. F. Dilworth

INVENTOR.
Herbert F. Yeakel
BY Edward Lawrence,
his ATTORNEY

UNITED STATES PATENT OFFICE.

HERBERT F. YEAKEL, OF PITTSBURGH, PENNSYLVANIA.

SANITARY WATER-CLOSET SEAT.

Application filed December 28, 1922. Serial No. 609,412.

To all whom it may concern:

Be it known that I, HERBERT F. YEAKEL, a citizen of the United States, and residing in the city of Pittsburgh, in the county of 5 Allegheny and State of Pennsylvania, have invented or discovered the new, useful, and Improved Sanitary Water-Closet Seats, of which the following is a specification.

My invention consists in a new and improved sanitary water-closet seat.

Generally speaking, my invention relates to that type of water-closet seat which is provided with a protective covering of paper, such paper being renewed, after each 15 use, by unwinding fresh paper from a supply roll and winding up the used paper on a receiving roll, the paper being provided with properly spaced apertures which are adapted to be brought into registration with 20 the seat opening.

More specifically my invention comprises a new and improved form of sanitary water-closet seat which may be stamped or otherwise formed of metal. I provide at either 25 side of the seat new and improved housings wherein are removably mounted the supply and receiving rolls for the apertured paper.

I also provide new and improved means for detachably mounting the rollers in their 30 housing.

Other novel features of construction and arrangement of parts will appear from the following description.

In the accompanying drawings, Fig. 1 is 35 a side elevation of a water-closet to which my improved seat is applied; Fig. 2 is a front elevation of the same; Fig. 3 is a perspective of the seat shown dismounted from the closet and with the paper and rollers 40 removed; Fig. 4 is a section taken along the line IV—IV in Fig. 3 but on a smaller scale; Fig. 5 is an enlarged, broken section taken along the line V—V in Fig. 2; Fig. 6 is a view showing the blank from which the 45 friction grips are formed, and Fig. 7 shows a portion of the paper web.

The following is a detailed description of the drawings.

A represents a closet bowl, and B represents 50 my improved closet seat.

Said seat is preferably pressed or otherwise formed of metal enameled in white or some other attractive color. The seat is provided with the usual buttal orifice 1, flanged 55 downwardly to present a smooth surface,

and the top of the seat at the front of the orifice is preferably concaved, as at 2, at either side of the medial line, to fit the legs. At the front and rear the seat is provided with a downwardly turned flange 3, the 60 hinge bolts 4 being attached to the rear flange.

The extremities of the flanges 3 are enlarged to form the ends 5 of the roll housings whose tops are inclosed by the outwardly and downwardly curved ends 6 of the top of the seat, said curved walls extending down to substantially the plane of the roll axes and being provided with in-turned, curved edges 7 over which the paper 70 will slip easily. The walls 6 are integrally connected at their ends with the end walls 5.

The end portions 5 of the flanges 3 at the front and rear of the seat are outset slightly, as shown in Fig. 3 and thus the curved portions 6 are slightly wider than the top of the seat from front to rear. This enables me to accommodate in the housings a roll of paper of sufficient width to entirely cover 75 the seat from front to rear.

The housing ends 5 are provided with central, circular holes 8 which form the bearings for the two rolls of paper.

Said rolls are wound on the card board rollers 9 which are detachably mounted in 85 the roll boxes axially alined with the bearings 8.

The method I prefer for mounting the rollers 9 is as follows.

10 represents knobs having annular seats 90 11 to receive the annular washers 12 of rubber or other material whose rear edge bears against the end 5 of the roll box. The inner ends of the knobs 10 are of reduced diameter to enter and be rotatably journaled 95 in the bearings 8.

To the inner ends of the knobs 10 are attached expansible spring gripping members which are inserted into and engage the bores of the rollers 9.

Thus in Figs. 5 and 6 I have shown the preferred form of said roll engaging members, the same being formed of a metal blank shown in Fig. 6 having two substantially spearhead like ends connected by an intermediate portion. The end portions have serrated edges and are bent rearwardly along the dotted medial line α so as to present angular cross sections, and the ends are bent forwardly at right angles along the 110

transverse dotted lines *b*, thus forming the spring gripping members 13 of angular cross section connected at their bases by the neck 14 which is provided with a central hole 15 through which a screw 16 is inserted into the inner end of the knob 10 at its axis.

When a roller is placed in one of the boxes, the spring fingers 13 of a pair of knobs are 10 compressed together with the fingers and said fingers are inserted through the bearings 8 into the bores of the rollers 9 until the inner portion of the knobs are journaled in the bearings with the washers 12 in snug 15 frictional engagement with the end walls of the roll boxes. The gripping members 13 then expand within the rollers, the four lateral edges of the former engaging the internal wall of the roller.

20 Thus, the rollers may be rotated by turning one of their knobs, but said rollers will not spin or turn too easily, owing to the friction between the washers and the ends of the roll housings.

25 In Fig. 7 I show a length C of the character of paper which I use in connection with my improved seat. Said paper is provided at proper intervals with orifices 17 of proper size to register with the orifice 1 of the seat and provided with serrated edges, as shown at 18, so as to form flaps which will bend down and cover the perimeter of the orifice 1, so that no portion of the body of the user 30 will come in contact with the material of the seat. The orifices 17 in the paper are properly spaced apart, so that when the paper is moved sufficiently to draw one orifice 17 from registration with the orifice 1 and superimpose the next orifice 17 in said 40 paper in registration with the orifice 1, the entire area of the seat is covered with freshly exposed and clean paper.

The paper C is rolled up on one of the rollers 9 and the roller is mounted, as above 45 described, in one of the roll housings. The loose end of the paper is then drawn across the seat and its end attached in any convenient manner to the empty roller which is then mounted in a similar manner in the 50 other roll housing. The last named or receiving roller is then rotated by means of its knob until the first orifice 17 in the roll of paper C comes into registration with the orifice 1. After the closet has been used, the receiving roller is rotated so as to wind up the used or exposed area of paper on the receiving roller and to unwind sufficient fresh paper from the supply roller to position the 55 second orifice 17 in registration with the orifice 1.

The operation is repeated after each use until all of the paper has been unwound from the supply roller and wound up on the receiving roller. The filled receiving roller 60 may then be removed and it and its burden

burned, the empty supply roller shifted to the receiving side and a loaded supply roller installed.

In unwinding from the supply roller and winding upon the receiving roller, the paper 70 traverses the rounded edges 7 and the rounded surfaces 6 without danger of catching or tearing, and insures a smoothly laid stretch of paper.

The paper when drawn across the seat will 75 be disposed in a horizontal plane, bridging the concavities 2, but will be pressed down into said cavities when the closet is in use. If the paper becomes wet, it may remain depressed into said cavities, but the first rotation of the receiving roller will draw the paper from contact with said cavities, and the subsequent rotation of said roller will draw the paper across the seat.

I prefer to use bag paper, as the same is of 80 sufficient tensile strength to insure its use without tearing.

It is evident from the foregoing that my 85 improved closet seat is a very substantial improvement, insuring complete sanitation 90 with but a minimum of trouble and expense. Thus in "paid closets" in public buildings, for the use of which a charge of five or ten cents is usually made, after each use, the attendant may enter the enclosure and wind 95 up the used area of paper and simultaneously unwind a fresh covering for the seat.

What I desire to claim is:—

1. A roller mounting for use in connection with sanitary water-closets and other purposes which consists of a pair of spaced apart supports provided with bearing holes, tubular rollers positioned between said supports in axial alinement with said holes, and journal members removably inserted from without into said bearing holes, said members being provided at their inner ends with expandible gripping fingers which are inserted into the ends of the rollers to detachably hold them in place.

2. A roller mounting for use in connection with sanitary water-closets and other purposes which consists of a pair of spaced apart supports provided with bearing holes, tubular rollers positioned between said supports in axial alinement with said holes, and journal members removably inserted from without into said bearing holes, said members being provided at their inner ends with expandible gripping fingers which are inserted into the ends of the rollers and the outer ends of said journal members being provided with knobs for the manual rotation of said roller.

3. A roller mounting for use in connection with sanitary water-closets and other purposes which consists of a pair of spaced apart supports provided with bearing holes, tubular rollers positioned between said supports in axial alinement with said holes,

journal members removably inserted from without into said bearing holes, said members being provided at their inner ends with
5 expandible gripping fingers which are inserted into the ends of the rollers to detachably hold them in place, and a compressible washer mounted on one of said journal

bearings and in frictional contact with the adjacent support to prevent spinning of the roller. ¹⁰

Signed at Pittsburgh, Pa., this 23rd day of December, 1922.

HERBERT F. YEAKEL.
